SLIDING FRAME FOR SHAKER CONVEYERS

Robert Moulton, Norristown, and Carrell J. Stover, Jenkintown, Pa., assignors to Goodman Manufacturing Company, Chicago, Ill., a corporation of Illinois

Application March 6, 1951, Serial No. 214,175

6 Claims. (Cl. 198—220)

1

This invention relates to improvements in sliding frames such as are employed in shaker conveyor systems for supporting the conveyor troughs. In such systems, the conveyor troughs usually consist of a series of trough-like members supported at their abutting or overlapping ends by sliding frame assemblies each comprising a base or stationary section and a reciprocal section. The adjacent ends of two contiguous troughs are secured one to another and to the reciprocal section of the sliding frame which constitutes a movable support which reciprocates on the base sections as the conveyor is reciprocated to effect movement of coal, gravel, grain, or other material along the conveyor line.

In mines, where such shaker conveyors frequently are employed, it becomes necessary at times to shift the position of the conveyor line or to add conveyor troughs thereto or to make other rearrangements of the conveyor troughs as the face of the coal or other mineral is advanced farther from the discharge end of the conveyor line. In coal mines in particular, where coal frequently is of less thickness than the average height of the miners, it frequently is necessary for the miners to move about in stooped positions and sometimes to crawl about portions of the mine on hands and knees. The manual transportation of conveyor lines, and particularly the above-mentioned sliding frames, under such conditions is laborious, since they are of sturdy steel construction and necessarily quite heavy. For the purpose of preventing relative sliding movement of the reciprocal sections with reference to the base sections and thus preventing possible injury to workmen's hands while such frames are being carried or dragged along the mine floor to the desired position or positions of use various devices have been provided. For example, pins have been used for securing the reciprocal section to the base section temporarily for the purpose stated as have automatically operated latching means which are released when the troughs are positioned on the reciprocal sections. The use of pins for securing the sections together has been found objectionable in some instances where workmen have failed to remove the pins to free the reciprocal section when the conveyor has been set up ready for use, whereby damage to the conveyor resulted. While the automatically operating latching means has been found to be satisfactory generally, the cost of manufacture of such latching means is relatively substantial and they are subject to damage

by rough handling and use to which the frames normally are subjected.

The principal object of the present invention is to provide an improved sliding frame having means of simple but durable construction for immobilizing the movable or reciprocal frame section with respect to the base section during handling, thereby avoiding injury to the workman or workmen moving the frame due to the tendency of the reciprocal section to slide to the limit of its travel in one direction or the other with respect to the base when the frame is tilted from a horizontal position. A more particular object of the invention is to provide an improved sliding frame the base section of which is provided with one but preferably two simple swingable handles or hand grips which, when one or both are grasped by a miner or miners for lifting or dragging, retains the movable frame section against relative sliding action but frees the reciprocal section when the handle or handles are released. The improvements thus have substantially the simplicity of the pins above referred to without being subject to the objection thereto mentioned above and can be provided at substantially less cost than can the automatically operated latching means, and in addition they have no spring actuated parts to get out of order but function satisfactorily to prevent the inadvertent sliding action of one section with respect to the other section during handling.

The character of the invention will be made clear by a consideration of the following specification and accompanying drawings wherein:

Fig. 1 is a broken plan view of a sliding frame which is illustrative of the present improvements;

Fig. 2 is a side elevation of the frame shown in Fig. 1;

Fig. 3 is an end elevational view of the frame shown in Fig. 1;

Fig. 4 is an end elevational view of the frame, on a reduced scale, with a shaker conveyor trough indicated thereon in dotted lines and showing struts or jacks which may be employed where necessary for anchoring the base section in position; and

Fig. 5 is an enlarged perspective view of the sliding frame.

It will be understood as the description proceeds that the invention is equally applicable to simple sliding frames in which one section operates directly on another as well as to roller and ball frames in which the sections are operated respectively by rollers and balls. Of these types

of sliding frames, ball frames are presently most widely used in mining and will be illustrated and described in connection with the present invention.

In the drawing, the ball frame specifically disclosed comprises a base section indicated generally by the numeral 10 and a movable or reciprocal section indicated generally by the numeral 11. The base section 10, in the particular form of the ball frame illustrated, comprises two transverse tie members 12 provided with teeth or cleats 13 adjacent the ends. The cleats 13 are of advantage where the ball frame is to rest upon the floor of a mine, since the teeth tend to prevent displacement of the base as the conveyor reciprocates. The ties 12 are shown as being attached together in parallel spaced relation by semi-cylindrical track members 14 which constitute portions of the two raceways for anti-friction balls. The tracks may be secured to the ties as by welding the same to angle members 15, which in turn are welded to the ties.

The reciprocal section 11 comprises two semi-cylindrical raceways or tracks 16 each arranged for cooperation with one of the tracks 14. Balls 16 are provided between each pair of raceways 14 and 16 as is well known whereby the members 16 are freely slideable to and fro through limited distances with reference to the tracks 14. The semi-cylindrical members 14 and 16 are provided with end portions 17 which may be welded in position. The tracks 16 are held in the properly spaced apart position by means of a transverse plate or web 18 which, in the particular form shown in the drawings, has a central raised portion 19 for stiffening purposes. The ends of the plate 18 are shown as being turned upwardly in the form of flanges 20 and preferably are welded to the respective sections 16. A pair of trough supports 21 are illustrated, each having an aperture extending horizontally therethrough for receiving a stud or like element by means of which two adjacent ends of contiguous trough sections such as the trough indicated at 22 in Fig. 4, may be secured to the reciprocal section 11. The particular means for securing the ends of the troughs together and to the trough supports 21 is no part of the present invention and is not illustrated. The flanges 20 are shown as being reinforced by plates 23 for providing a more sturdy support for the members 21.

In assembling the various parts of a shaker conveyor system, ball frames are located along the line of the conveyor at positions for supporting adjacent ends of contiguous conveyor trough sections. Where necessary, struts or jacks indicated by the numeral 24 in Fig. 4 may be employed for anchoring the base sections 10 against displacement, the jacks having portions that bear against the mine roofs.

Within coal mines it is generally necessary to transport the ball frames manually to the positions at which they are to be used, and as stated above, under some conditions of use in coal mines where the roof of the mine is low, the placement of such ball frames, due to their weight, sometimes constitutes a difficult chore. Since the reciprocal sections 11 are freely movable on the base sections, by reason of the ball construction, throughout the limits of their permitted travel, it is desirable to provide means for immobilizing the reciprocal sections to prevent possible injury to the workmen's hands during handling. For securing the two sections together for the purpose of preventing relative movement, we have pro-

vided handles or hand grips at opposed sides of the ball frame which, when both or either one is grasped by workmen in lifting the frame to a carrying position or for dragging it, will grip the movable section and thus immobilize it relative to the base section during such transportation of the frame. The hand grips shown are indicated by numerals 25 and are of U shape with outwardly turned end portions 26 extending through apertures in lugs 27 which are welded to the upper intermediate portions of the track members 14. One of the ends 26 of each hand grip is provided with an extension 28 which is adapted to overlie and frictionally engage an upper portion of the adjacent semi-cylindrical track 16 whenever the handle is raised to substantially the horizontal position shown in dotted lines in Fig. 3 by a workman in grasping the handle and raising it. The grasping and raising of the hand grips 25 by a workman in lifting or dragging a frame immobilizes the movable section with respect to the base section. When the handle or handles are released, they gravitate to the full line position shown in Fig. 3 and thus in effect automatically release the reciprocal section 11.

It has not been found necessary to provide socket recesses or the like in the track members 16 for receiving the extensions 28 of the handles to form a positive locking connection between the frame sections during handling. The described automatic braking provided by the handle or handles 25 for immobilizing of the reciprocal frame section avoids injury to the workmen's hands which frequently has resulted in the past where no immobilizing means for the reciprocal section has been provided.

While we have shown simple hand grip members which, when grasped by a workman, effect immobilization of the reciprocal frame member with respect to the base member, it will be obvious that various changes in the particular form illustrated may be resorted to without departure from the invention defined by the appended claims.

What is claimed is:

1. In a sliding frame for supporting a shaker conveyor trough line, a base section provided with tracks, a reciprocal frame section provided with track members reciprocal to and fro along the tracks of the base section, and means for immobilizing the reciprocal section relative to the base section during manual transportation of the frame comprising a handle pivotally secured to the base section for movement between upper and lower positions and a member operable by the handle into braking contact with a track member of the reciprocal section when the handle is grasped and moved to the upper position in lifting the frame.

2. In a sliding frame for supporting a shaker conveyor trough line, a base section provided with tracks, a reciprocal frame section provided with track members reciprocal to and fro along the tracks of the base section, and means for immobilizing the reciprocal section relative to the base section during manual transportation of the frame comprising a handle pivotally secured to one of the sections for movement between operative and inoperative positions and provided with an extension swingable into braking contact with the other section when the handle is grasped and moved to the operative position in moving the sliding frame.

3. In a sliding frame for supporting a shaker conveyor trough line, a base section provided with tracks, a reciprocal frame section provided

with tracks reciprocal to and fro along the tracks of the base section, means on the base section for pivotally supporting a hand grip, and a hand grip pivotally mounted on said track of the base member and arranged normally to hang in 5 pendant relation at the side of the base member and provided with a portion movable into braking contact with the adjacent track of the reciprocal section for restraining sliding movement thereof with respect to the base section upon the manual grasping of the hand grip and elevation of the same about the pivots thereof in moving the sliding frame.

4. In a sliding frame for supporting a shaker conveyor trough line, a base section provided with 15 tracks, a reciprocal frame section provided with tracks reciprocal to and fro along the tracks of the base section, spaced apart apertured lugs arranged in pairs and secured to the tracks of the base section, and handles each comprising a 20 U-shaped hand grip portion provided with oppositely extending end portions pivotally mounted in the apertures of a pair of said lugs and a brake section extending from one of said ends of each handle in a direction to engage the reciprocal frame section when the respective handle has been moved about the pivoted end portions thereof in bodily moving the frame.

5. In a sliding frame for supporting a shaker conveyor trough line, a base section provided with 30 a pair of track members, a reciprocal frame sec-

tion provided with a pair of track members slideable to and fro along the tracks of the base section, a normally pendant handle pivotally attached to one of the tracks of the base section and a member movable by the handle into contact with the adjacent track member of the reciprocal frame for restraining sliding movement thereof relative to the base section when the handle is moved manually in lifting or dragging the frame.

6. In a sliding frame for supporting a shaker conveyor trough line, a base section provided with a pair of ball track members, a reciprocal frame section provided with a pair of ball track members located intermediate the tracks of the base section and slideable to and fro along the same, and handles each pivotally secured to one of the track members of the base section at opposite longitudinal sides thereof and normally hanging pendant at said sides and each comprising a hand grip adapted to be swung upwardly to a substantially horizontal position when grasped in lifting the ball frame and provided with an extension arranged to engage the adjacent track 25 of the reciprocal frame section for restraining sliding movement of the reciprocal frame section.
